UNITED STATES PATENT OFFICE.

JOSEPH V. CLARK, OF CINCINNATI, OHIO, ASSIGNOR OF TWO-THIRDS TO
GEORGE E. WALTON AND NOBLE K. ROYSE, BOTH OF SAME PLACE.

MACHINE FOR GRINDING AND POLISHING BALLS.

SPECIFICATION forming part of Letters Patent No. 423,512, dated March 18, 1890.

Application filed March 31, 1888. Serial No. 269,185. (No model.)

To all whom it may concern:

Be it known that I, JOSEPH V. CLARK, a citizen of the United States, and a resident of the city of Cincinnati, in the county of Hamilton and State of Ohio, have invented certain new and useful Improvements in Machines for Grinding and Polishing Balls, of which the following is a specification.

The several features of my invention and the advantages arising from their use, conjointly or otherwise, will be apparent from the following description.

In the accompanying drawings, forming part of this specification, Figure 1 is a side elevation of my device. Fig. 2 is a front view. Fig. 3 is a section taken at the line *x x*, Fig. 2. Fig. 4 is a section taken at the line *y y*, Fig. 2.

The frame A has the yoke B dovetailed to it and adapted to move vertically in the grooves. A lug *a* projects from the frame A and has a screw *a'* screwed through it. The yoke B rests on the screw *a'* and is adjusted vertically by means of it. The shaft C is supported between the arms *b* of the yoke B. The preferred form of bearing for the shaft C is that shown in the drawings, where bearing-screws *b'*, passing through the ends of the yoke-arms, are received in sockets in the ends of the shaft. A clamp-screw *b*² is provided, which holds in place the bushing *b*³, the latter receiving the screw *b'*. When desired, the entire shaft C may be withdrawn through the upper yoke-arm by loosening the screw *b*². The disk D is clamped to the shaft C by any suitable means. Its lower surface is provided with the polishing and grinding facing *d*, which is preferably an emery-disk. The lower disk E is preferably provided with a hub *e*, and the whole is centered on the axle F. The lower part of the axle F is provided with an annular flange *f*, which, being received into a corresponding recess in the hub *e*, serves to support the lower disk. The axle F is supported on the bracket A', projecting from the stationary frame A. The plate G is attached to the top of the axle F and occupies a space between the two disks, preferably touching neither. This plate G is of irregular outline, it being shown star-shaped in Fig. 4. In the same plane with plate G is the plate G', sup-

ported by the bracket G', projecting from the frame A. The plate G' has an irregular opening cut in it corresponding to the shape of plate G, so that when the two plates are centered a channel *g*, everywhere of the same width, exists between them. The disk being fixed in position by its attachment to the frame A, the space between the disks is regulated by the adjusting-screw *a'*.

The device is employed for grinding and polishing various kinds of balls—for example, such as are employed in roller-skates and bicycle-bearings. It is also employed in shaping and polishing balls of any description which require to be absolutely spherical, such as billiard-balls, balls for check-valves, &c.

The mode of operation is as follows: The balls in the rough are placed in the channel *g* and motion imparted to one of the disks—for instance, the disk D—by a band passing around its hub *d'*. This causes the balls to rotate, and a secondary rotation in the opposite direction of the lower disk is then produced; or the lower disk may be fixed or positively rotated in the same or opposite direction by a driving-belt around its hub *e*, or, as is preferably the case, be left free to rotate by the revolution of the balls being ground. With the irregular channel as a guide, the balls are turned in every direction and are soon reduced to a perfectly spherical shape, and are highly polished. It is not necessary that the polishing-disk *d* should be attached to the upper disk D, although preferably so. The exact shape of the channel *g* is not important. It should be irregular in shape so as to insure turning the balls in all directions. The sharpness of its curves will depend upon its width, and the relation of the size of the balls to the diameter of the disks. The plates forming the channel may be omitted and a channel cut in the lower disk. The lower disk may be employed to positively rotate and to have a roughened disk and be employed to grind the balls, and in such case the upper disk may be allowed to be freely rotated by the balls being ground or be positively rotated and have roughened surface and assist in positively grinding the balls. In the device as shown in the drawings the

lower disk is smooth and case-hardened and the upper disk is roughened.

What I claim as new, and desire to secure by Letters Patent, is—

5. 1. In a machine for grinding balls, the combination of two opposing plates and an intermediate plate or portion provided with a channel extended around the axis of the plate and approaching to and receding from the 10 said axis, substantially as and for the purposes specified.

2. The combination of two concentric opposing disks or plates provided with driving hubs, an intermediate plate having channel 15 alternately approaching and receding from the axis of this plate, a shaft to which one of the disks is rigidly attached, and an independent support for the other disk, substantially as and for the purposes hereinbefore set 20 forth.

3. The combination of disk or plate D, polishing-disk attached thereto, shaft C, disk E, rigidly connected to axis F, channeled plate G, mounted on axle F and centered on axis C and 25 concentric with disk E, bracket supporting axle F, and independent plate G' and bracket supporting it, the plates G and G' being so related as to form between them a channel alternately extending in undulating lines to 30 and from the axis of said plates G and G', substantially as and for the purposes set forth.

4. The combination of disk or plate D, pol-

ishing-disk attached to disk D, shaft C, supported in vertically-adjustable yoke B and 35 having disk D rigidly attached to it, axle F, surrounding shaft C, plate G, mounted on axle F and concentric with disk D, disk E e, centered on axle F, bracket supporting axle F and disk E, and plate G' and bracket supporting it, the plates G and G' being so related as to form between them a channel approaching to and receding from the center of said plate G, substantially as and for the purposes hereinbefore set forth.

5. The combination of frame A, provided with lug a, screw a', yoke B, provided with arms b, shaft C, disk D, rigidly attached to shaft C, disk E, and bracket A', supporting plate G', substantially as and for the purposes mentioned.

6. The combination of the concentric disks D and E and the provision for guiding the balls located between disks D and E alternately to and from the center and the periphery of the disks, substantially as and for the purposes specified.

7. The combination of the upper arm b, bushing b³, set or clamping screw b², bearing-screw b', shaft C, lower arm b, and bearing A', substantially as and for the purposes specified.

JOSEPH V. CLARK.
